United States Patent Office.

EDWARD HEATON, OF NEW HAVEN, CONNECTICUT, ASSIGNOR TO C. B. WHITTLESEY, OF SAME PLACE.

Letters Patent No. 64,766, dated May 14, 1867.

IMPROVEMENT IN SUSPENSORY BANDAGES.

The Schedule referred to in these Letters Patent and making part of the same.

TO ALL WHOM IT MAY CONCERN:

Be it known that I, EDWARD HEATON, of New Haven, in the county of New Haven, and State of Connecticut, have invented a new and useful Improvement in Suspensory Bandage; and I do hereby declare the following, when taken in connection with the accompanying drawings and the letters of reference marked thereon, to be a full, clear, and exact description of the same, and which said drawings constitute part of this specification; and represent a front view.

My invention relates to an improvement in supporters for the testicles, and consists in the peculiar construction whereby all parts are made to fit the person, and easily adjusted.

To enable others to construct and apply my improved bandage, I will proceed to fully describe the same as illustrated in the accompanying drawings.

I form the parts entirely of linen, stitched together, so that the whole may be washed as any linen garment.

A is the pouch, sewed on to the body-piece B, which is curved, as seen in the drawing, so as to fit the person, C. Ordinarily this part of the bandage is made straight, depending upon the flexibility of the material to conform to the body, the opening for the penis, its edge protected by a linen binding, gathered or fulled, as denoted in the drawing, so that the binding of the opening will lie flat upon the penis, and prevent irritation from the edge of the opening, as in bandages of common construction. In fitting this part, care should be exercised that the opening be not too large, for if sufficiently large to allow any portion of the "sack" or "glands" to protrude, the bandage is a greater injury than benefit. From the body-piece a strap, D, is attached, passing over the hip joint, is buckled or otherwise secured to a similar strap, E, from the other side; these two straps are curved to fit the form of the person, that is, so as to lie flat, whereas, were they not so curved, they soon fold and wrinkle, to the great discomfort of the wearer. Other straps, F, attached to the pouch A, pass around the leg, and buckle or otherwise secure to their respective buckles H H.

Some of the advantages of my improvement are, first, the strain and weight are solely upon the hips; second, by its construction it is durable, and easily adjusted; third, there is no elastic substance used in the construction, which, as soon as the elasticity was impaired, ruined the bandage; fourth, it may be cleaned in like manner as ordinary linen.

The mode of adjustment, after the foregoing description, will be understood without further explanation.

Having therefore thus fully described my invention, I do not wish to be understood as broadly claiming a suspensory bandage, but what I do claim as of my invention, and new and useful, and desire to secure by Letters Patent, is—

The combination of the pouch A, having the opening C, protected in the manner described, with the body-piece curved, formed, and attached thereto as shown and described, and the straps D and E, also curved, formed, and attached to the said body-piece as set forth, the whole constructed and arranged in the manner herein specified.

EDWARD HEATON.
